UNITED STATES PATENT OFFICE.

JOHN J. QUACKENBUSH, OF LAKEVIEW, NEW JERSEY.

BLIND-FASTENER.

SPECIFICATION forming part of Letters Patent No. 729,892, dated June 2, 1903.

Application filed March 3, 1903. Serial No. 145,933. (No model.)

To all whom it may concern:

Be it known that I, JOHN J. QUACKENBUSH, a citizen of the United States, residing in Lakeview, in the county of Passaic and State 5 of New Jersey, have invented certain new and useful Improvements in Blind-Fasteners; and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

15 My invention relates to attachments for blinds or shutters having pivoted slats, and it has for its object to provide a device of the general nature above indicated designed especially for securing the slats of the blind or 20 shutter either open or closed, and, as a further object, to provide a mechanism which shall comprise in a single organization means for both securing the slats of the blind or shutter and for securing closed the blind or 25 shutter itself.

My invention will be found fully illustrated in the accompanying drawings, wherein—

Figure 1 is an inside view of blinds or shutters provided with my attachment. Fig. 2 is 30 a horizontal sectional view of the blinds, taken just above the attachment constituting my invention and showing the slats held closed. Fig. 3 is a view similar to Fig. 2, but showing the slats held open; and Fig. 4 is a vertical sectional view taken just to the right of the 35 attachment, as seen in Fig. 1.

On the meeting rail of each blind or shutter *a*, hinged in the casement *b* in the usual manner, is secured an elongated plate *c*, extending vertically. At the outer edges of these plates are arranged leaves *d*, which are pivotally attached to the plates by means of hinges *e*, whose pivots stand out from the plane of the plates in such manner that 40 when the leaves are swung around on the hinges into the position shown in Fig. 3 there is clearance between the adjacent edges of each plate and the leaf. The object of this will be explained later. Each leaf is bent 45 longitudinally at right angles, so that when the leaf lies against the face of the meeting rail of the blind the bent-off portion *f* extends

around the edge of the meeting rail and takes against several of the slats of the blind, it being understood that said slats are at this 55 time in their closed position. In order to lock the leaves in the position just described as that where they hold the slats closed, I provide a latch or bar *g*, having its pivot on a stud *h*, which may project from one of the 60 plates *c*. The blinds being closed, this latch is held in the horizontal or securing position by means of a keeper *i*, which may be conveniently attached to the other plate *c*. In order to prevent the latch being manipulated from 65 the outside of the blind, a guard *j* is pivoted on one of the plates *c* in such manner that when suspended vertically from its pivot *k* it takes against the top of the latch to hold the same down in the keeper. Latch *g* is also 70 adapted to secure the slats in their open position. To this end, and as best seen in Fig. 3 and also in dotted outlines in Fig. 4, latch *g* is made long enough so that it extends, when in the horizontal position, in the path of movement of two of the pivoted slats in each blind. It is, furthermore, preferably made of such 75 width as to just fill the space between two adjacent slats in each blind when the same are in their open position. (See Fig. 4.) In order 80 that the slats may assume the open position and yet be engaged by the latch, leaves *d* are swung back into the position shown in Fig. 3, so that the clearance above referred to as then existing between the hinging edges of the 85 leaves and the plates *c* will permit the latch to be turned into engagement with the slats, as best seen in Fig. 3. It will be understood that in locking the slats open, since the moving of the latch on its pivot to the horizontal 90 position means that one end thereof must be depressed while the other is elevated, of course the two series of slats must be first arranged in relatively reverse positions, so that when they are to be locked by the latch they will 95 properly coat therewith so as to receive it between the two receiving-slats in each series.

In order to secure the shutters closed, one of the plates *c* is formed with an extension *l*, which extends downwardly and to which is secured one member of a hasp *m*, whose other or slotted member *n* receives a turn-button *o*, whose shank *p* is threaded and screwed into a plate *q*, secured to the casement-sill *r*. By

providing the button with a threaded shank
its head can be screwed down fast against the
hasp, so as to prevent its being manipulated
from the outside into the position where its
head will coincide with the slot in the slotted
member of the hasp.

Having thus fully described my invention,
what I claim as new, and desire to secure by
Letters Patent, is—

- 5 1. The combination, with a blind having a series of pivoted slats, of a securing member adapted to engage said series of slats to maintain them closed, said member being pivoted on the blind and having its pivotal axis extending transversely of the slats, and means for locking said member in the securing position, substantially as described.
- 10 2. The combination of the blinds each having pivoted slats, of securing members adapted to engage said slats to maintain them closed, each of said members being pivoted on a blind and having its pivotal axis extending transversely of the slats, and a common means for securing said members in the securing positions, substantially as described.
- 15 3. The combination of the blinds each having pivoted slats, of securing members adapted to engage said slats to maintain them closed, each of said members being pivoted on a blind

and having its pivotal axis extending transversely of the slats, and a pivoted latch adapted to engage in common both of said members to lock the same in the securing positions, substantially as described.

4. The combination, with the blinds each having a series of pivoted slats, of a pivoted securing member adapted to engage each series of slats between two of the same to maintain said slats in the open position, substantially as described.

5. The combination of a casement, a blind arranged in said casement and having pivoted slats, and means for securing the slats in fixed relation to the blind and the blind in fixed relation to the casement, said means consisting of a relatively stationary member fixed to the blind, hinged members carried by said fixed member and one of which is adapted to engage the slats, and means for interlocking the other hinged member with the casement, substantially as described.

In testimony that I claim the foregoing I have hereunto set my hand this 20th day of February, 1903.

JOHN J. QUACKENBUSH.
